UNITED STATES PATENT OFFICE.

VALFRID NILSSON, OF STOCKHOLM, SWEDEN, ASSIGNOR TO THE FIRM OF
C. O. RYDHOLM & CO., OF STOCKHOLM, SWEDEN.

CRAVAT-HOLDER.

No. 853,591.

Specification of Letters Patent.

Patented May 14, 1907.

Application filed December 11, 1905. Serial No. 291,271.

To all whom it may concern:

Be it known that I, VALFRID NILSSON, foreman, a subject of the King of Sweden, residing at Stockholm, Sweden, and whose post-office address is Lästmakaregatan 29, Stockholm, Sweden, have invented a new and useful Cravat-Holder; and I do declare the following to be a full, clear, and exact description of the invention, such as will enable others skilled in the art to which it appertains to make and use the same, reference being had to the accompanying drawings.

This invention relates to improvements in cravat holders and more particularly to that class which are fixed to the cravat and serve to hold the same in the desired position by gripping or engaging the collar button.

The invention consists in the provision of a holder of this character comprising a main body portion provided with a button gripping device and split to permit of yielding action in gripping the button, the said split body portions being united and held in gripping or locking relation with respect to each other by a resilient member fixed to split portions.

The object of the invention is to provide a neat and compact holder of the general character set forth adapted to grip and to be engaged with various sized collar buttons and so constructed that its yielding action is relatively extensive so that its engagement and disengagement with and from the collar button may be easily effected without injury either to the holder or the button.

The invention will be more fully described in connection with the accompanying drawing and will be more particularly pointed out and ascertained in and by the appended claims.

In the drawing: Figure 1 is a rear view of a cravat showing an improved holder embodying the main features of my invention secured thereto. Fig. 2 is a face view of the holder on a slightly enlarged scale. Fig. 3 is a like view of the reverse side to that shown in Fig. 1. Fig. 4 is a section on line 4—4 of Fig. 2. Fig. 5 is a section on line 5—5 of Fig. 2.

As shown the invention consists of a holder comprising a main body portion of a generally circular formation provided with a button gripping slot 4. Said slot is preferably open and extends from the central portion of the holder outwardly through the outer edge

thereof and is provided with a relatively contracted entrance 5 and a relatively enlarged base portion 6. The entrance portion is preferably rounded at 7 to facilitate engagement of the holder with the button. When the holder is in place the contracted central portion 6 engages the neck of the button, the head thereof overhanging the margins of said central portion.

In order to provide a compact holder and enable the same to lie closely upon the cravat and to prevent bulging the central portion of the holder is depressed at 18 as shown in Fig. 4 to receive the head of the button, there being formed a flat portion 9 apertured at 10 to permit the holder to be sewed to the cravat. Obviously the holder can be secured to the cravat in any desirable manner.

In order to provide sufficient yielding action of the holder in gripping various sized buttons and to thereby enable the holder to be readily attached and detached the same is split at 2 from the central portion 6 of the slot outwardly to form substantially two gripping or holding sections 11 and 12 which sections are united and held in gripping relation by suitable resilient means which in the preferred embodiment of the invention consists of the following construction. The sections 11 and 12 are recessed at 13 and 14 to receive the resilient wire 3 which may be anchored in the holder in any suitable manner. The wire 3 is preferably anchored in place by lugs 15 and 16 which as shown are formed integral with the split portions 11 and 12 and which are bent inwardly to engage the wire 3. If desired the wire 3 may be soldered. Said wire 3 extends across the split portion 2 and substantially throughout the length of the peripheral portion of the holder.

The holder is stitched to the cravat a by means of thread b or other securing means in a manner to cause the depressed portion 18 to project inwardly toward the button, and to cause the open portion of the button gripping slot to face upwardly. The cravat is pulled downwardly so that the contracted portion 5 engages the neck of the button on the lower side thereof whereupon the cravat is raised upwardly a sufficient distance to cause the contracted or entrance portion 5 to spring over the neck of the button and cause the same to engage the enlarged or base portion 6 of the slot.

It will be obvious from the foregoing that the holder will securely anchor the cravat in place and prevent the same from either slipping up on the collar or being displaced laterally with respect thereto.

I claim:-

1. A cravat holder comprising a main body portion provided with a button gripping device and split into two parts to permit of yielding action in gripping the button, and a resilient member associated with said split body portion.
2. A cravat holder comprising a main body portion provided with an open button gripping slot having a relatively contracted entrance and an enlarged base portion, the holder being split from the slot outwardly into two parts, and a spring connecting said split portions.
3. A cravat holder comprising a main body portion provided with an open button gripping slot, the holder being split from the slot outwardly into two parts, and a spring uniting said split portions.
4. A cravat holder comprising a main

body portion provided with an open button gripping slot, the holder being split from the slot outwardly and having a portion of its periphery of circular formation recessed with respect to the body portion of the holder, and a resilient wire fixed in said recess and uniting the split portions of said holder.

5. A cravat holder comprising a main body portion provided with an open button gripping slot, said portion being split from the slot outwardly and having a portion of its periphery of circular formation recessed with respect to the body portion of the holder, and a resilient wire fixed in said recess and uniting the split portions of said holder, the slotted portion of said holder being depressed to receive the head of the button.

In testimony whereof I affix my signature in presence of two witnesses.

VALFRID NILSSON.
